BUTTER TUB RECONDITIONING MACHINE

Milton P. Swearingen, Decatur, Ind.

Application June 17, 1935, Serial No. 27,121

1 Claim. (Cl. 147—1)

This invention relates to woodworking machinery and more particularly to a butter tub reconditioning machine.

The primary object of this invention resides in the provision of a machine adapted to hold butter tubs in position for planing or smoothing their outer peripheries.

Another object of this invention resides in the provision of a machine adapted to hold butter tubs or the like in rotary position for application of smoothing devices against their outer peripheries by workmen stationed at opposite ends of the machine.

A further object of this invention resides in the provision of a machine adapted to rotatably hold butter tubs at its opposite ends for application of smoothing devices in the hands of workmen stationed in convenient reach of individual controlling means for the tub upon which each is operating.

A still further object of this invention resides in the provision of a machine adapted to frictionally retain butter tubs at the outer ends of rotary counter-shafts driven from a main power shaft and controlled by means in convenient reach of workmen stationed at the opposite ends of the machine.

In addition to the aforesaid objects this invention resides in the provision of a machine comprising opposed counter-shafts provided with chucks fixed on their outer ends and connected to a main power shaft by suitable driving means permitting each counter-shaft to be stopped and started at the will of workmen operating on the outer peripheries of the tubs.

Aside from the foregoing objects, this invention resides in the provision of a butter tub reconditioning machine, which among other elements, consists of end standards and an intermediate standard suspended therebetween by truss-rods connecting the end standards, said standards having aligned bearing boxes mounted thereon.

With these and other objects in view this invention resides in certain novel features of construction to be hereinafter set forth in the specification, illustrated in the accompanying drawings and pointed out in the appended claim and, while the disclosure depicts my present conception of this invention, the right is reserved to resort to such variations in construction as come within the scope of the claim.

In the accompanying drawings forming a part of this application:

55 Fig. 1 is a side view of a butter tub recondi-

tioning machine as constructed in accordance with this invention.

Fig. 2 is an end view thereof.

Fig. 3 is a vertical sectional view on line 3—3 of Fig. 1.

Fig. 4 is a detail horizontal sectional view on line 4—4 of Fig. 2.

Fig. 5 is a detail perspective view of a portion of the belt shifting fork.

In the present embodiment of this invention the numeral 5 designates, in general, a machine adapted to rotatably support butter tubs at its opposite ends for the application of planing or smoothing devices held or controlled by workmen stationed adjacent the rotating tubs.

The aforesaid machine constituting the subject matter of this application preferably consists of substantially inverted V-shaped standards 6 suitably secured to sills 7 and having their legs 8 connected by cross-beams 9 adapted to support suitable bearing boxes 10 at their medial points, said bearing boxes 10 being disposed in alignment to support a main shaft 11.

Suspended between the standards 6 as by truss-rods 12 and braces 13 is an intermediate standard 14 of substantially inverted V-shape configuration somewhat similar to the standards 6.

Suitably secured in alignment on the upper ends of the standards 6 and 14 is any approved type of bearing boxes 15 in which is journaled 30 opposed counter-shafts 16 and 17, each having a pulley 18 splined thereon adjacent each of which is a loose pulley 19.

Secured to the outer ends of the aforesaid counter-shafts 16 and 17 are chucks 20 of substantially frusto-conical configuration for the reception of butter tubs or the like. These chucks are preferably covered with a rubberized or other suitable frictional material 21 so the tubs when pushed thereon will rotate with the counter-shafts and be easily removed upon completion of smoothing the outer peripheries thereof.

Secured or otherwise secured to the main shaft 11 are wide pulleys 22 which are connected to the pulleys 19 by belts 23 or other suitable power transmitting means.

Disposed between pulleys 22 in splined relation to the main power shaft 11 is a power pulley 24 adapted to be connected by any suitable power transmitting means such as a belt 25 or the like to a source of power herein shown by dotted lines as an electric motor 25'.

Secured to and extending from the cross-beams 9 are arms 26 adapted to pivotally support hand-

levers 27 which are disposed at one side of the standards 6 adjacent the chucks 20.

Connecting the standards 6 on that side thereof upon which the levers 27 are mounted is a beam 5 28 having secured thereto adjacent its medial point spaced guide brackets 29 for loosely supporting the free ends of belt shifting rods 30 suitably connected to the hand-levers 27 as shown in Fig. 6. The belt shifting rods 30 are provided with forks 31 as shown in Fig. 5 and, through the instrumentality of the same, power is transmitted from the constantly rotating main shaft 11 to either or both of the counter-shafts 16 and 17 by the belts when the hand-levers are pushed or 10 rocked inwardly.

With this invention constructed as aforesaid, it is manifest that a machine is provided whereby butter tubs can be readily reconditioned in an expedient manner and, through the particular disposition of the controlling means, the workmen at opposite ends of the machine can conduct their work individually. Further, through the instrumentality of the particularly constructed frame vibration is reduced to the minimum. 15

Having thus fully described my invention what I claim and desire to protect by Letters Patent is:

A butter tub reconditioning machine of the character set forth comprising spaced substantially V-shaped standards, sills supporting the standards, cross beams secured to the legs of the standards, a main power shaft journaled on said cross beams, an intermediate substantially V-shaped standard of lesser length than the first mentioned standards disposed above the plane 5 upon which the base of the first mentioned standards rest, means connecting the intermediate standard to the legs of the first mentioned standards, opposed counter shafts journaled on the upper extremities of the standards with their inner ends terminating at the intermediate standard, yielding chucks secured to the outer ends of the counter shafts, power transmitting means connecting the main power shaft with the counter shafts, and means associated with the power transmitting means for disposing the power transmitting means in idling position relative to the counter shafts. 10

MILTON P. SWEARINGEN.
